UNITED STATES PATENT OFFICE.

FREDERICK RAPP, OF CHICAGO, ILLINOIS.

DESIGN FOR A WATCH-CASE.

SPECIFICATION forming part of Design No. 17,349, dated May 17, 1887.

Application filed March 1, 1887. Serial No. 229,369. Term of patent 14 years.

To all whom it may concern:

Be it known that I, FREDERICK RAPP, a citizen of the United States, residing at Chicago, in the county of Cook and State of Illinois, 5 have invented a new and original Design for Watch-Cases, which is fully set forth in the following specification, reference being had to the accompanying drawing, forming a part hereof.

10 My design for a watch case is in the form of a mermaid bent backward in the form of a circle and provided with wings upon its back, which are of circular form, fitting within the curved back of the mermaid, said mermaid 15 being the representation of the well-known

ancient myth, whereof the upper half is in the form and figure of a female human being and the lower half in the form of a fish.

The pendant is shown, in this case, held between the hands of the mermaid.

What I claim is—

The design for a watch-case, the same consisting of the representation of a mermaid curved backward in a circular form and provided with wings on the back, and a pendant 25 or stem, as described and shown.

FREDERICK RAPP.
